UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

APPARATUS FOR TREATING FILAMENTS.

1,026,345.

Specification of Letters Patent.

Patented May 14, 1912.

Application filed February 13, 1907, Serial No. 357,141. Renewed January 27, 1911. Serial No. 605,074.

To all whom it may concern:

Be it known that I, WILLIAM D. COOLIDGE, a citizen of the United States, residing at Schenectady, county of Schenectady, State of New York, have invented certain new and useful Improvements in Apparatus for Treating Filaments, of which the following is a specification.

This invention comprises an apparatus for the production of incandescent lamp filaments by treatment of wire containing refractory material.

The apparatus is in many respects automatic and is adapted for operation on a roll of ductile wire to produce filaments properly shaped and properly treated for mounting in incandescent lamps.

I have found that non-ductile material, such as tungsten and other refractory elements or compounds, may be incorporated in a ductile alloy, such as cadmium amalgam, and that the product so formed may be extruded into ductile wires of small cross-section. An amalgam suitable for this purpose may contain fifty parts of mercury to fifty parts of cadmium, and the tungsten powder or other refractory component of the squirming mixture may be added to the amalgam in the proportion of thirty-nine per cent. by weight. The amalgam is warmed to a pasty condition and the tungsten is introduced therein by rubbing the mixture in an ordinary chemists' mortar. The mixture can be extruded through a diamond die when slightly warmed. Such ductile wire and the method of producing it form the subject of my application, Serial No. 377,781, filed June 7, 1907.

According to my present invention I make lamp filaments from the ductile wire above described, or from other filamentary conductor requiring similar treatment, by use of an apparatus such as is shown in the accompanying drawings.

Figure 1 is a sectional elevation of a chamber in which the treating operation is carried on. Certain of the elements are represented diagrammatically; Fig. 2 is a diagram illustrating the time during which the several circuits carry current; and Fig. 3 is a diagram to illustrate how the circuits are controlled from a single rotating shaft.

The apparatus illustrated in Fig. 1 comprises an envelop 1 of glass or metal provided with a cover 2 cemented thereto or made tight by means of a suitable gasket.

This chamber is provided with an outlet 3 by which connection may be made with an air pump and through which the chamber may be exhausted. Within this chamber is supported a reel 4 carrying a considerable quantity of ductile wire such as that above described. Coöperating with the reel are means for unwinding the wire, for looping it up in a straight loop, for passing a small current through the loop to drive out the mercury and cadmium, for increasing the current to sinter the residue into a coherent body, for disconnecting the finished loop from the untreated wire and dropping it into a suitable receptacle, and for repeating these operations in regular order until the wire on the reel has been converted into filaments. The specific means for carrying out these various acts are hereinafter set forth in more detail.

When the apparatus is set up, the outer end of the coil of wire on the reel is threaded through a small but rigidly mounted eye 5 and passed between rollers 6 and 7. These rollers are mounted at the ends of movable levers 8 and 9 pivotally supported on axes 10 and 11, and geared together so that when arm 8 moves up arm 9 moves down and the rolls 6 and 7 separate. A coiled spring 12 initially holds the rollers in contact on the ductile wire. Immediately in front of the movable rollers and in direct line with the wire is a tweezer-shaped spring clip 13 mounted on the end of a movable arm 14. This clip is adapted to move forward and take hold of the end of the ductile wire and then recede for a distance of ten or twelve inches to unwind the ductile wire from the spool. The clip is then restored to its initial position and the filament sags down in the form of a loop 15, as shown in the drawings. To secure this movement of the spring clip 13, an electromagnet 16 is provided, with suitable levers connecting with the movable arm 14 on which the spring clip is mounted. These connections consist of a lever 17, pivoted at 18 and having a lower slotted end 19 engaging with a pin located a short distance above the pivotal point 20 of arm 14. A coiled spring 21 engages with lever 17 and tends to keep arm 14 in the lowered position indicated in dotted lines in the figure. This tendency is counteracted by the pull of electromagnet 16 during the entire cycle of treatment, except for that particular part during which the wire is to

be unreeled and shaped into a loop. During that interval the electromagnet is unenergized and the spring is free to move the arm 14 and its attached clip.

5 Assuming that the ductile wire on spool 4 has been threaded through the eye 5 and projects as far as the rollers 6 and 7, the operation of the device is as follows: A strong current is passed through electromagnet 16 to cause the tweezer-shaped clip 13 to approach the end of the ductile wire. As it does so it passes under the influence of electromagnet 22 and the latter attracts an armature 23 carried on the clip and thereby 10 opens the clip, so that the wire may pass in between the two lips of the clip. At this stage of the operation the rollers 6 and 7 are held apart by the action of electromagnet 24 on the pivoted arm 8. The clips are 15 free to move up some little distance along the wire. This movement is subject to the retarding action of a flat spring 26 carried on arm 14 and put under compression by a rigidly mounted stud 27. A set-screw 28 20 controls the limit of movement. When the clip reaches a position well up on the wire, the electromagnet 22 is deenergized and the two jaws or lips of the clip 13 come together on the wire and take a firm hold thereon.

25 Electromagnet 16 is then deenergized and coiled spring 21 operates through the connected levers and arms to swing clip 13 around through an arc into the position shown in dotted lines, thereby unreeling a 30 considerable length of ductile wire from reel 4. Two pads of felt 28' serve to control the unreeling of the wire. The felt pads 28' are stationary except for the spring support of the upper one and pinch lightly on the 35 amalgam wire passing between them. There is also a spring bearing on the top of the reel 4, as shown in the drawing, which also to some extent controls the unreeling of the wire, both this spring and the felt pads 40 45 serving to keep the wire from shooting by or crowding on through loop 5 after the regular length of wire has been pulled out by the spring clip 13. Immediately after the unreeling of the wire, electromagnet 24 50 is deenergized, and rollers 6 and 7 approach each other and engage with the wire. Electromagnet 16 is then energized with a relatively weak current to bring the clip into the position shown in the drawing and to 55 form a loop out of the unreeled wire. Current is then passed through the filament by way of arm 8, roller 6, clip 13, and arm 14 and the filament is heated at a low temperature until the mercury and cadmium distill 60 therefrom. A water-cooled jacket 25 may be utilized for condensing the vaporizable components of the wire. This jacket is shaped like a half moon and extends on three sides of the filament to condense the 65 metal vapors given off during the heat treat-

ment. The current is then automatically increased and the filament brought quickly to bright incandescence, in which condition it is maintained for a short time to insure vaporization of all easily vaporizable components and sintering of the refractory particles of which the wire is composed. The ductile components of the wire have by this treatment all been removed so that the wire now consists of non-ductile material. To 70 secure release of the treated filament from the clip 13 and rollers 6 and 7, it is only necessary to separate the rollers and move the clips forward as if the operation were to be begun. The treated loop then drops into the glass vessel 29 arranged immediately below and remains there until the entire reel of wire has been worked up and until the treating chamber is opened to receive a new reel of wire. The easy release 80 or disconnection of a treated loop from the supply of untreated wire may be attributed to the fragile nature of that portion of the wire in contact with the rollers and with the clip. The thermal conductivity of these 85 parts is sufficient to prevent complete sintering of the portions in immediate contact, and these portions are therefore much weaker than the filament itself.

I have above indicated a certain sequence 90 in the excitation of the several electromagnets and circuits, and I have indicated in Fig. 1 a rotating shaft 30 provided with commutators for carrying out these steps. Each of the six commutators mounted on 100 this shaft is provided with a segment of conducting material connected with the shaft and having an angular width proportional to the time during which the particular circuit controlled by that commutator is to receive current. A common source of electrical energy 31 may be employed, and suitable resistances 32 may be connected in series with the various devices to control the current flowing therethrough. 110 A commutator 33 supplies current to electromagnet 24 to separate rollers 6 and 7. Commutators 34 and 35 control current to electromagnet 16 and serve to give it a weak current to hold clip 13 in the position shown 115 in the drawing, or to give it a strong current to force the clip forward toward the rollers, or lastly, to give it no current at all so that spring 21 may swing the clip through a long 120 arc. Commutator 36 controls the current to the electromagnet 22 for opening the jaws of the spring clip 13. Commutators 37 and 38 control the current through the filament itself and give it a weak current during the early stage of treatment, and high current 125 during subsequent stages.

Figs. 2 and 3 illustrate diagrammatically the magnitude and relation of the time intervals during which the several circuits are energized. This diagram is intended to 130

- show how the various switch or commutator segments should be proportioned and arranged in order to automatically energize the electromagnets, etc., at such time intervals as will enable them to carry out the series of acts resulting in finished filaments. The sectors on Fig. 2 having angular widths corresponding to time intervals and having radii indicative of the magnitude of current in the several circuits and are numbered to correspond with the electromagnets and filament of Fig. 1. A circuit is simultaneously established through electromagnets 22 and 24 and very shortly thereafter through electromagnet 16. The last named electromagnet is energized by strong current. Then electromagnet 22 is deenergized to permit the spring clip 13 to engage with the protruding end of ductile wire; then electromagnet 16 is deenergized to permit the spring clip to swing through an arc. Shortly thereafter electromagnet 24 is deenergized to permit rollers 5 and 6 to contact with the wire. Electromagnet 16 is then energized with a smaller current to restore the clip to its initial position. Simultaneously, or shortly thereafter, the filament 15 receives a low current to vaporize the mercury and cadmium. After a brief interval current through filament 15 is increased to sinter the tungsten or other refractory material into a coherent and strong filament. Throughout the entire time of filament treatment electromagnet 16 is energized to hold the clips in the position shown in the drawings.
- Fig. 3 illustrates an arrangement of commutators suitable for producing the effects above recited.
- What I claim as new, and desire to secure by Letters Patent of the United States, is,—
1. The combination of a container, means for exhausting the air therefrom, a spool of ductile wire within said container, means for unreeling a section of said wire and for shaping it into a loop, means for supplying current to said loop to treat the same, and means for separating the treated loop from the untreated wire.
  2. The combination of a container, a supply of ductile wire therein, automatic means for forming a portion of said wire into a loop, means for supplying current to said loop to produce changes therein, and means for separating the treated loop from the supply of wire.
  3. The combination of a container, a supply of ductile wire therein, and automatic means for treating successive portions of said wire with current and for separating said portions.
  4. The combination with a sealed envelop, a reel of wire therein, means for unreeling,
- ing a predetermined length of said wire and for shaping it into a loop, means for supplying a relatively low current to said loop, automatic means for increasing the current to heat the loop to incandescence, and means for releasing the treated loop to make room for a second length of wire.
5. The combination of a sealed envelop, a ductile conductor therein, means for shaping a predetermined length of said conductor into a loop, means for supplying current thereto to treat the conductor, and automatic means for repeating this treatment on successive lengths of said conductor.
6. The combination of a container, a supply of unfinished filamentary conductors therein, and automatic means for successively incandescing portions of said supply with current passed therethrough while the container remains sealed.
7. The combination of a sealed container, a supply of unfinished filamentary conductors, automatic means for successively moving predetermined and equal lengths of said conductor into position for treatment with current in said sealed container, and means for supplying a sintering current to the conductor under treatment.
8. The combination of a container, means for removing the air therefrom, a supply of unfinished filamentary conductors containing refractory material within said container, and automatic means for successively producing sintered filaments from said supply of unfinished conductors while the container is maintained free from oxygen.
9. In an apparatus for the continuous treatment of filament, the combination of a source of raw filament containing a binder, means for taking raw filament from such source and giving it the general shape which it is desired that the finished filament should have, and means for treating such shaped raw filament first at low temperature and then at high temperature to eliminate the binder therefrom and sinter the final material of the filament.
10. In an apparatus for the continuous treatment of refractory metal filament, the combination of a source of raw filament containing binder, means for feeding said raw filament from said source, means for passing through successive portions of said raw filament as it is fed from the source first a relatively low current to heat it sufficiently to expel the binder and then a higher current to sinter the final refractory metal.
- In witness whereof, I have hereunto set my hand this 12th day of February, 1907.
